CEMENTING TOOL

Le Roy Brown, Huntington Park, Calif.

Application June 25, 1940, Serial No. 342,302

6 Claims. (Cl. 166—1)

This invention relates to a cementing tool whereby different areas within a bore hole, the casing or the liner may be cemented.

An object of my invention is to provide a novel cementing tool, including spaced packers, there being an opening between the packers through which cement may be forced, and including means to permit the circulation of fluid through the tool while the tool is being run into the well.

Another object of my invention is to provide a novel cementing tool of the character stated, provided with a valve which controls the longitudinal passage through the tool, said valve being manually controllable after the tool is in position in the well.

Another object is to provide a novel cementing tool of the character stated, which is effective in operation, and the passage therethrough being opened or closed at will by the operator to enable cement to be forced through an opening between spaced packers.

Other objects, advantages and features of invention may appear from the accompanying drawing, the subjoined detailed description, and the appended claims.

In the drawing:

Figure 1 is a side elevation of my cementing tool.

Figure 2 is a longitudinal, quarter, sectional view of the same.

Figure 3 is an enlarged fragmentary, longitudinal, sectional view of the valve and tube in which it is seated.

Referring more particularly to the drawing, my cementing tool 1 is essentially tubular and open from top to adjacent the bottom thereof although the tubular body of this tool is made up of a number of parts which are threaded together to form the whole as will be more specifically described.

At the upper end of the tool, a pipe 2 is provided, to the upper end of which a slip head 3 is secured. The slip head is preferably screwed onto the pipe 2, and the drill pipe (not shown) screws into the head 3. A plurality of slips 4 are mounted in the head 3, and these slips are moved into engagement with the casing or liner of the well by a plurality of spring arms 5, which surround the pipe 2 and are connected to the slips by links 6. The slips 4 are normally held in retracted position when the tool is being run into the well, and when the area to be cemented is reached, the arms 5 are released by disengagement from a pin 7 (all of which is usual and

well-known), thereby permitting the slips 4 to be moved outwardly into engagement with the casing on downward movement of the tool relative to the arms 5 and the slips 4. Spaced packers 8 and 9 are arranged on the tool below the slip assembly, and these packers surround the tubular body of the tool and closely engage the wall of the casing. The packers 8 and 9 are preferably mounted on sleeves 10 and 11 respectively, which are screwed together, the sleeve 10 in turn screwing into the upper part of the tool and the sleeve 11 screwing into or onto the lower part of the tool. A hole 12 between the packers 8 and 9 permits cement to pass outwardly from the tool between the packers after the desired point in the well has been reached.

A bottom shoe 13 forms the bottom of the body of the tool, and a fluid port 14 in the shoe enables fluid to pass out of the body of the tool below the packers 8 and 9 while the tool is being run in the well. After the tool has reached the position in the well which the operator desires to cement, the longitudinal passage 15 through the tool is closed by the following arrangement:

10 A valve stem 16 extends into the bottom of the tool, and its lower end is provided with spring fingers 17, which are fixedly attached to the stem. These fingers drag against the inside of the casing while the tool is being run into the well. 20 Packing 18 is provided in the shoe 13 and bears against the valve stem 16, substantially as shown in Figure 2. This packing is held in position and is pressed against the valve stem by the gland 19. This gland is provided with coarse inside threads, 30 and the valve stem 16 is provided with threads 20 from the outside thereof which screw into the gland, thus enabling the valve stem to be moved longitudinally relative to the tool on rotation of the tool, the valve stem being held stationary by 35 the spring fingers 17. A valve 21 is provided on top of the stem 16, and this valve seats on top of the sleeve 11 below the port 12, as shown in Figure 2. In order that the valve 21 may not be accidentally seated or unseated, I provide a lost motion connection between the valve and the stem 16. This lost motion connection may include an enlarged window 22 in the valve stem, the valve 21 being provided with a pin 23 which extends into this window. The pin 23 projects 40 from a pintle 24, which fits into the top of the valve stem, as shown in Figure 3. A coil spring 25 surrounds the stem of the valve 21, and normally urges the valve onto its seat. When the tool is being run into the hole, the valve 21 is 45 lifted off of its seat, and thus fluid can pass 50 55

downwardly through the tool and out through the fluid port 14.

When it is desired to cement a section of the casing, the tool is rotated and since the spring fingers 17 are bearing against the casing, the valve stem 16 will be held stationary. The threads 20 will be screwed downwardly in the gland 19 by this rotation of the tool until the valve 21 rests on its seat on top of the sleeve 11. Cement is now forced downwardly through the drill pipe and into the tool, and this cement passes outwardly through the port or ports 12 between the packers 8 and 9 to complete the cementing job.

Having described my invention, I claim:

1. A cementing tool comprising an elongated hollow body, a pair of spaced packers mounted on the body, said body having an outlet port between the packers, a valve seated in the body below said port, said body having a fluid outlet port below the valve and below the lowermost packer, and means operable on movement of the tool to open or close said valve, said means including a valve stem depending from the valve and projecting from the bottom of the tool, wall engaging means on the lower end of the valve stem said valve and valve stem being longitudinally movable in the body, whereby the valve may be opened or closed on movement of the body of the tool relative to the valve.

2. A cementing tool comprising an elongated hollow body, a pair of spaced packers mounted on the body, said body having an outlet port between the packers, a valve seated in the body below said port, said body having a fluid outlet port below the valve and below the lowermost packer, and means operable on movement of the tool to open or close said valve, said means including a valve stem depending from the valve and projecting from the bottom of the tool, wall engaging means on the lower end of the valve stem, threads on the valve stem, said threads screwing into threads in the body of the tool whereby rotation of the tool body relative to the valve stem will move the valve into open or closed position.

3. A cementing tool comprising an elongated hollow body, a pair of spaced packers mounted on the body, said body having an outlet port between the packers, a valve seated in the body below said port, said body having a fluid outlet port below the valve and below the lowermost

5 packer, means operable on movement of the tool to open or close said valve, said means including a valve stem depending from the valve and projecting from the bottom of the tool, wall engaging means on the lower end of the valve stem said valve and valve stem being longitudinally movable in the body whereby the valve may be opened or closed on movement of the body of the tool relative to the valve, and means yieldably 10 mounting the valve on said valve stem.

4. A cementing tool comprising an elongated hollow body, a slip assembly mounted on the upper end of the body, a pair of spaced packers mounted on the body below the slip assembly, 15 said body having an outlet port between the packers and a fluid port below the lower packer, a valve seated in the body below the first-named port, a valve stem depending from the valve and projecting from the bottom of the body, and wall 20 engaging means on the lower end of the valve stem whereby relative movement of the valve stem and tool body will open or close the valve.

5. A cementing tool comprising an elongated hollow body, a slip assembly mounted on the upper end of the body, a pair of spaced packers mounted on the body below the slip assembly, 25 said body having an outlet port between the packers and a fluid port below the lower packer, a valve seated in the body below the first-named port, a valve stem depending from the valve and 30 projecting from the bottom of the body, and wall engaging means on the lower end of the valve stem whereby relative movement of the valve stem and tool body will open or close the valve, 35 and means yieldably mounting the valve on the valve stem.

6. A cementing tool comprising an elongated hollow body, a slip assembly mounted on the upper end of the body, a pair of spaced packers 40 mounted on the body below the slip assembly, said body having an outlet port between the packers and a fluid port below the lower packer, a valve seated in the body below the first-named port, a valve stem depending from the valve and 45 projecting from the bottom of the body, wall engaging means on the lower end of the valve stem, external threads on the valve stem, said threads screwing into internal threads in the body whereby rotation of the tool body relative to the valve stem will open or close the valve.

LE ROY BROWN.
